CLAIM

The ornamental design for a chair-to-desk lock, as shown and described.

DESCRIPTION

FIG. 1 is a top front perspective view of a chair-to-desk lock showing my new design;

FIG. 2 is a bottom front perspective view thereof;

FIG. 3 is a top rear perspective view thereof;

FIG. 4 is a front view thereof;

FIG. 5 is a rear view thereof;

FIG. 6 is a top view thereof;

FIG. 7 is a bottom view thereof;

FIG. 8 is a left side view thereof;

FIG. 9 is a right side view thereof;

FIG. 10 is a cross sectional view taken along line 10-10 in FIG. 8; and,

FIG. 11 is an environmental top front perspective view thereof showing a plurality of bristles.

The broken line showing of the bristles in FIG. 8 illustrates the environment of the claimed design and forms no part thereof.
